C. P. Zepfel
ATTORNEY

UNITED STATES PATENT OFFICE

HUBERT DALTON, OF STAMFORD, CONNECTICUT

SMOKER'S STAND

Application filed April 23, 1930. Serial No. 446,498.

This invention relates to smoker's stands, and has for its general object and purpose to provide a simply constructed, ornamental and serviceable stand provided with means for receiving and extinguishing lighted cigar and cigarette butts, as well as ashes, burned matches and other waste, and which will to a material degree, thereby prevent the dissemination of objectional odors into the atmosphere of the room.

It is another and more particular object of the invention to provide a smoker's stand embodying a base structure and a hinged cover therefor, together with novel means for mounting or supporting a water containing bowl or receptacle within said base structure.

It is another detail object of the invention to provide supporting means for the water containing bowl in the form of a cradle constructed and mounted in the base of the stand whereby the bowl will always be sustained or suspended in a perpendicular position to obviate spilling or discharge of the water therefrom in the event that the stand is accidentally knocked over or tilted to various angular positions.

It is another important feature of the invention to provide the hinged cover of the stand with a central directing tube or post together with a table top of improved construction having a central depending tubular portion engaged by the upper end of said post, and novel means for rigidly securing the several parts in assembled relation.

It is also a further general object of the invention to provide a smoker's stand, the several elements of which are of simple mechanical form so that the stand may be produced at comparatively small manufacturing cost.

With the above and other objects in view, the invention consists in the improved smoker's stand, and in the form, construction and relative arrangement of the several parts thereof as will be hereinafter more fully described, illustrated in the accompanying drawings, and subsequently incorporated in the subjoined claims.

In the drawings, wherein I have disclosed one simple and practical embodiment of the invention, and in which similar reference

characters designate corresponding parts throughout the several views,—

Fig. 1 is a vertical sectional view through a smoker's stand embodying the several novel features of my present improvements; 55

Fig. 2 is a top plan view;

Fig. 3 is a horizontal section taken on the line 3—3 of Fig. 1;

Fig. 4 is an enlarged detail section taken on the line 4—4 of Fig. 1; 60

Fig. 5 is an enlarged detail sectional view taken on the line 5—5 of Fig. 3, and

Fig. 6 is a fragmentary sectional view showing the parts of the stand in a horizontal position while the water containing bowl retains its normal perpendicular position. 65

Referring in detail to the drawings, the base structure of the stand includes a hollow top section 5 which may be of any desired ornamental shape or form and is entirely open at its top. This top section 5 is rigidly supported on the upper end of a tube 6 of suitably predetermined length, said upper end of the tube being seated within an annular flange 7 formed on the bottom wall of the section 5. The lower end of said tube is positioned within a similar annular flange 9 formed on an ornamental cover member 8 rabbeted at its lower end as at 10 to receive the boss 11 provided upon a footed base section 12. It will of course, be understood that the particular form or shape of the parts 6, 8 and 12 is not of importance, insofar as the novel mechanical features of the device are concerned and may be varied as desired. 70

These several parts, together with the top section 5 of the base structure are rigidly tied or secured together by means of the rod 13 which is extended downwardly through the opening 14 in the bottom wall of the section 5 and is threaded at its lower end as shown at 15, in a central opening formed through the boss 11 of the base section 12. 75

The upper portion of the stand includes an inverted hollow cover section 16, a length of tubing 17 having its lower end seated within the annular flange 18 on the top of the cover section to retain said tube in alignment with the opening 19 of said cover section, and a table 20. This table is in the form of a metal 80

85

90

95

100

casting having an annular portion affording a table top of appreciable width and a central downwardly extending tapering tubular portion 21, the wall of which at its lower end, 5 is rabbeted as at 22 to receive the upper end of the tube 17.

The parts 16, 17 and 20 are rigidly secured together by means of the ornamental vertical standards 23 engaged at their lower 10 ends upon the horizontally disposed annular part 24 of the cover section 16 and having threaded bores to receive the attaching screws 25 disposed through openings provided in the part 24. The upper ends of the standards 23 15 are horizontally extended and engaged against the under side of the table 20, said ends of the standards being provided with openings therein to receive the screws 26 which are adapted to be threaded into suitable bores provided in the ends of the arms 20 of a carrying handle 27 which bridges or extends diametrically across the upper open end of the tapering part 21 of the table.

The cover section 16 is hingedly connected 25 with the top section 5 of the base structure for radial movement relative thereto. The parts of this hinge shown at 28 are of suitable ornamental form and riveted or otherwise secured to the walls of the base section 30 5 and cover section 16 respectively. The opposed edges of these walls are recessed or rabbeted as indicated at 29 so that when the cover section is in closed position, the outer surfaces of the walls of said sections will be 35 positioned substantially in the same curvilinear plane.

At the diametrically opposite side of the device with respect to the hinge 28, the members 30 and 31 are secured to the walls of 40 the base section 5 and the cover 16 respectively, and are preferably of the same ornamental form as the parts of the hinge 28. The member 30 has a hollow part 32 in which a latch pin 33 is slidably mounted and is urged to its latching position by the spring 34, one end of said pin being provided with a suitable finger piece or knob 35. The other member 31 is provided with a part 36 having a socket 37, and when the cover section 16 45 is in closed position, this socket is in alignment with the bore of the part 32. Thus the latch pin 33 being projected by the spring 34 into the socket 37, holds the top structure of the stand in its erect or perpendicular position and retains the cover section 16 thereof in a tightly closed position upon the base section 5.

Within the base section 5 of the stand, a water containing bowl or receptacle 38 is removably supported. Preferably I suspend this bowl in a swinging cradle, said cradle as herein shown, embodying an outer ring 39 and an inner ring 40. The inner ring is connected with the outer ring at diametrically spaced points by suitable pivots 41 while the

outer ring 39 is pivotally mounted upon the wall of the base section 5 at diametrically opposite points as shown at 42, the said pivots 42 being disposed at right angles to the pivots 41 connecting the rings with each other. 70

The bowl 38 which may be of glass or other suitable material preferably has its wall tapered inwardly as indicated at 43 to restrict the diameter of the top opening 44 of said bowl. Intermediate of its ends, the wall of the bowl 38 is provided with an external annular flange or bead 45. This bead is adapted to rest upon the upper edge of the inner cradle ring 40 as clearly shown in Figs. 5 and 6 of the drawings and to said ring, the upwardly extending holding springs 46 are suitably secured, said springs at their upper ends being formed to snap over the bead or flange 45 of the bowl 38 and thereby releasably hold said bowl in its suspended position, 80 within the ring 40.

It will be evident from the above description that the bowl is supported by the cradle out of contact with the walls of the base section 5 and cover section 16, and said bowl is so proportioned relative to the internal dimensions of the parts 5 and 16 that in all positions of the stand and in the relative swinging or pivoting movement of the cradle rings 39 and 40, the bowl will not contact with said 90 walls. Thus as shown in Fig. 6 of the drawings, if the stand is accidentally knocked over to a horizontal position, the two cradle rings will either swing together relative to the wall of the base section 5 or the inner ring 40 will 100 pivot within the outer ring 39 so that the normal perpendicular position of the bowl or receptacle 38 will be maintained, thus preventing the discharge or spilling of the water contained therein. 105

In the use of the improved smoker's stand above described, when disposed in the normal upright position as shown in Fig. 1, ashes or lighted cigar or cigarette butts will be dropped through the central opening of the 110 table top and the part 21 and directed by the tube 17 into the bowl 38, the upper open end 44 of which is disposed immediately beneath the lower end of the tube 17 and the opening 19 in the cover section 16. Thus the ignited tobacco is instantly extinguished so that the disagreeable fumes or odors from smouldering tobacco will be obviated. The top 20 of the stand provides a convenient table or support for glasses, plates or other articles in 115 serving refreshments. The arms of the handle 27 may be provided with suitable rests or supports as shown at 47 which are preferably located over the central opening in the table so that ashes from cigars or cigarettes disposed upon said supports will drop through said opening and the top surface of 120 the table thus kept clear of ashes.

It will be apparent that by the provision of the means above described for separably and 125

rigidly connecting the parts 20 and 27 with each other and detachably securing the same upon the upper end of tube section 17, table top sections 20 and handles 27 of numerous different sizes and ornamental forms may be interchangeably used and assembled in connection with parts 5, 6, 16, and 17 of standard form. Thus, without requiring the retailer to stock a large number of complete stands the individual esthetic tastes of respective purchasers may be catered to. Also, it will be evident that by producing a stand of this kind in the form of separable parts rigidly united or held in assembled relation, a large number of the similar individual parts of the stand can be very compactly arranged, thus reducing to a very appreciable extent, the space occupied by such parts in storage or shipment in comparison with that which would be required if the stand were produced in a single unit having permanently assembled inseparable parts.

From the foregoing description considered in connection with the accompanying drawings, the several novel features of my improved smoker's stand will be clearly understood. The construction of the several parts thereof and the means provided for connecting the same in assembled relation enables such assemblage to be very easily and quickly made, with an assurance of an absolutely rigid relationship between the several parts of the stand. When it is desired to empty the bowl 38 of the waste matter collected therein, it is only necessary to pull the latch pin outwardly against the action of the spring 34 so that the entire upper structure of the stand including the cover section 16, may be radially swung to one side of the upper open end of the base section 5. The bowl 38 may then be readily lifted from the swinging cradle and after discharge of its contents and cleaning, is refilled with water and then replaced in the cradle. After returning the upper part of the stand to its perpendicular position and latching the same in connection with the base structure, the stand is then in condition for further use. An article of this kind, constructed in the manner above explained, is susceptible of embodiment in numerous different ornamental forms, but in view of the relative simplicity of the several parts thereof, such stand can be manufactured and sold at comparatively small cost. While I have herein shown one practical and preferred embodiment of the device, it will nevertheless be understood that the essential features thereof may also be incorporated in various other alternative structures, and I accordingly reserve the privilege of resorting to all such legitimate changes therein as may be fairly embodied within the spirit and scope of the invention as claimed.

I claim:

1. A stand of the kind described compris-

ing a hollow base section, a cover hinged to said base section, and means mounted within the base section for removably supporting a collection receptacle in spaced relation to the walls thereof and for swinging movement relative thereto.

2. A stand of the kind described comprising a hollow base section, a cover hinged to said base section, a cradle for supporting a collection receptacle out of contact with the walls of said base section, said cradle consisting of an annular member pivotally supported upon the walls of said base section, and means pivotally connected with said member for removably supporting the receptacle in suspended relation thereto.

3. A stand of the kind described comprising a hollow base section, a cover hinged to said base section, a cradle for supporting a collection receptacle out of contact with the walls of said base section, said cradle consisting of an annular member pivotally supported upon the walls of said base section, and a second annular member positioned within said first named member and connected therewith for pivotal movement about axes disposed at right angles to the pivotal axes of the first named member and adapted to receive and support the collection receptacle in suspended relation to said members.

4. An article of the kind described comprising a hollow base section, a cover section hinged upon said base section, means mounted within the base section for supporting a collection receptacle in spaced suspended relation to the walls thereof, said means including parts connected for relative pivotal movement in angularly related planes to sustain said receptacle in a perpendicular position in various angular positions of the stand, means for releasably latching the cover to the base section, and means carried by said cover section for directing waste materials into said collection receptacle.

5. In an article of the kind described, a hollow base section, a cover section hinged to said base section, a collection receptacle supported in said base section, said cover section having an opening at the top thereof, a table top having a central downwardly extending tubular portion open at its upper end, a tube interposed between said cover and the lower end of the tubular part of the table, means rigidly and separably connecting said cover section and the table with each other and in assembled relation with said tube, and means for releasably latching said cover section in its closed position to the base section.

6. A smoker's stand comprising a housing having a hinged cover section provided with an opening in the top thereof, means mounted within said housing for supporting a liquid containing collection receptacle in a perpendicular position with its upper open end adjacent to the opening in said cover, a table

130

5 top having a central opening therethrough, means for rigidly and detachably supporting said table top in spaced relation above the housing cover, and separable means for directing waste matter deposited through the opening in the table top through the opening in said housing cover and into said collection receptacle.

10 7. In a smoker's stand, a waste collecting receptacle, means for supporting said receptacle in a perpendicular position, a cover for the upper open end of the receptacle hinged upon the supporting means, a table provided with a central opening therethrough, said cover having an opening in the top thereof, a separate waste directing tube interposed between the opening in the table and the opening in said cover, and standards extending between and rigidly fixed to the cover and the table for retaining the same together with said directing tube in rigidly assembled relation to each other.

15 8. In a smoker's stand, a waste collecting receptacle, means for supporting said receptacle in a perpendicular position, a cover for the upper open end of the receptacle hinged upon the supporting means, a table provided with a central opening therethrough, said cover having an opening in the top thereof, a waste directing tube interposed between the opening in the table and the opening in said cover, a carrying handle arranged above and extending across the opening in the table, standards fixed at their lower ends to the cover, and a common means securing the upper ends of said standards and the ends of said handle to the table and whereby the table, the cover and said directing tube are secured together as a rigidly assembled unit.

20 9. In a smoker's stand, a supporting pedestal, a housing mounted upon said pedestal including a base section and a cover section arranged thereon, a cradle mounted in the base section of the housing consisting of pivotally connected annular members movable through angular paths relative to each other, said cover section of the housing having an opening in the top thereof, a liquid holding receptacle provided with means on the wall thereof to engage one of said annular members whereby said receptacle is removably supported in the cradle in a perpendicular position and with its upper open end in alignment with the opening of the cover section to receive waste matter deposited through said opening, and means for releasably latching said cover section in closed position.

25 10. A stand of the kind described comprising upper and lower tubular sections, means arranged between and connecting said sections to enclose and removably support a collection receptacle, a table top having a central opening through which material is adapted to be deposited and provided with

30 ing the upper end of said upper tubular section, and means for rigidly and detachably securing said table top in assembled relation with said upper tubular section, whereby table tops of various sizes and shapes may be interchangeably assembled with said tubular section of the stand.

35 11. A stand of the kind described comprising upper and lower tubular sections, means arranged between and connecting said sections to enclose and removably support a collection receptacle, a table top having a central opening through which material is adapted to be deposited and provided with a seat concentric with said opening receiving the upper end of said upper tubular section, a carrying handle separable from the table top, and means for rigidly securing the handle and table top to each other including parts detachably secured to said receptacle enclosing means and rigidly securing the table top in assembled relation with said upper tube section, whereby table tops and carrying handles of various sizes and forms may be interchangeably assembled with said tube 40 section of the stand.

45 In testimony that I claim the foregoing as my invention, I have signed my name hereto.

HUBERT DALTON.
